UNITED STATES PATENT OFFICE.

JOHN A. WHITE, OF OXFORD, OHIO.

MOP-WRINGER.

No. 923,391.

Specification of Letters Patent.

Patented June 1, 1909.

Application filed March 18, 1908. Serial No. 421,424.

To all whom it may concern:

Be it known, that I, JOHN A. WHITE, a citizen of the United States, residing at Oxford, in the county of Butler and State of Ohio, have invented certain new and useful Improvements in Mop-Wringers, of which the following is a specification, reference being had therein to the accompanying drawings.

10 This invention relates to mop wringers, and the object of the same is to provide such a wringer with means for preventing the edge of the mop from escaping from between the ends of the rollers.

15 With this object in view my invention consists in certain novel features of construction hereinafter to be described, and then more particularly pointed out in the claims.

In the accompanying drawings, Figure 1 is a vertical section of a mop pail showing the mop wringer with my invention applied thereto; Fig. 2 is a detail view of the wringer with the guard in its idle or normal position; Fig. 3 is a similar view with the guard in its operative position, and Fig. 4 is a top plan view of the pail with the mop wringer mounted therein.

In these drawings, I have illustrated the preferred form of my invention and have shown the same as applied to a well-known form of mop wringer comprising a pair of rollers 1 and 2 placed substantially parallel and provided with axles 3 adapted to engage bearings in suitable brackets 4 and 5. These rollers are normally spaced a slight distance apart and one of the rollers, here shown as 2, is movable relatively to the other roller, this movement being permitted by providing elongated bearing slots 6 for the axles of said roller. The movable roller 2 is held in its normal position close to the roller 1 by means of suitable springs 7 and 8 which permit the same to move away from that roller. These rollers are preferably of a length considerably less than the diameter of the pail in which they are mounted, thus enabling the mop to be inserted from the side of the wringer, that is, between the inner ends of the rollers. The bearing bracket 5, in which the outer ends of the rollers or the ends lying nearest the side of the pail are mounted, is preferably a continuous bracket, supporting the axles of both rollers and extending across the space between said rollers at the outer ends thereof, thus effectually preventing the escape of the mop from that end of the

roller. It is necessary, however, that the space between the rollers remain open at the inner end in order that the mop may be inserted therein, but this also permits the edge of the 60 mop to escape from between the ends of the rollers as the same is being drawn between the rollers.

In order to permit the mop to be inserted between the rollers and the ends of this open 65 space then closed to prevent the escape of the mop therefrom, I provide a suitable guard which is adapted to be actuated by the rotation of one of the rollers, as the mop is drawn between the same, to close the 70 space between the rollers to prevent the escape of the mop. This guard preferably comprises a plate 9 which is loosely mounted on the axle 3 of the movable roller 2 between the inner end of that roller and 75 its supporting bracket 4. This plate fits closely between the supporting bracket and the adjacent end of the movable roller, and, while the weight of this plate is, preferably, such as to cause the same to normally hang 80 in substantially a vertical position, thereby leaving the space between the rollers 1 and 2 open at the inner end thereof, the relative positions of the plate and the adjacent end of the roller are such that when said roller is 85 rotated about its longitudinal axis the frictional contact will be sufficient to overcome the weight of the plate and the plate will be turned about its pivotal center and caused to move along with the roller, this movement being in such a direction as to move the plate into position across the space between the rollers 1 and 2. This movement of the plate 9 continues until the free end of the same has come into contact with the 90 bearing bracket 4 which supports the adjacent end of the fixed roller 1, and which forms a stop for the free end of the plate and retains the same in position across the space between the two rollers, thus effectually 95 closing this space at the inner end of the rollers. While the frictional contact between the plate and the roller may, under normal conditions, be sufficient to move the plate, this frictional contact is increased by 100 a slight longitudinal twisting or turning movement of the roller in its bearings, thus causing the end of the roller to pinch the plate 9 between the same and the bearing bracket. This twisting movement of the roller may be caused by the irregularities in 105 the thickness of the mop, which, when it

has been inserted between the rollers, tends to force the movable roller 2 away from the fixed roller 1, and, owing to the irregularities thereof, one end of the movable roller 5 will be moved a greater distance than the other end, thus producing the twisting movement of the roller. As soon as the mop has 10 been removed from between the rollers and the springs have returned the movable roller 2 to its normal position, the frictional contact between the plate 9 and the end of the roller 2 will be removed and the plate will drop to its normal or inoperative position. The plate 9 preferably has the upper corner. 15 of the free end thereof cut away, as shown at 10. to prevent the same catching in the threads or fabric of the mop and thus preventing the operation of the guard. From the foregoing description it will be 20 apparent that I have provided a guard which will close the space between the two rollers of the mop wringer in such a manner as to prevent the escape of the mop from the ends of the rollers after it has once been inserted between the same. It will be further 25 apparent that the device can be readily attached to mop wringers of types other than that herein shown and that the guard itself can be modified to adapt the same to existing conditions, and, therefore, I wish it to 30 be understood that I do not desire to be limited to the exact details of construction shown and described, for obvious modifications will occur to a person skilled in the art. 35 Having thus fully described my invention,

what I claim as new and desire to secure by Letters Patent, is:—

1. A mop wringer comprising a pair of rollers, and a guard carried by one of said rollers and adapted to be actuated by the rotation of said roller to close the space between said rollers at one end thereof. 40

2. A mop wringer comprising bearing brackets, rollers having axles journaled in said bearing brackets, and a guard comprising a plate mounted on one of said axles between the roller and its bearing bracket and adapted to be moved into its operative position by the rotation of said roller. 45

3. A mop wringer comprising a pair of rollers, one of said rollers being movable relatively to the other, bearing brackets for said rollers, a guard comprising a plate loosely mounted between one end of said movable roller and its bearing bracket and adapted to be actuated by the rotation of said movable roller when the same has been moved relatively to the other roller. 50

4. A mop wringer comprising a pair of rollers, and a guard movably supported near one end of said rollers and adapted to be actuated by the rotation of one of said rollers to close the space between said rollers at one end thereof. 60

In testimony whereof, I affix my signature in presence of two witnesses.

JOHN A. WHITE.
